UNITED STATES PATENT OFFICE.

WARREN N. BOWERS, OF JEFFERSON, ALLEN COUNTY, ASSIGNOR OF ONE-HALF TO HENRY C. BOWERS, OF NEW HAVEN, INDIANA.

GATE.

SPECIFICATION forming part of Letters Patent No. 287,361, dated October 23, 1883.

Application filed April 3, 1883. (Model.)

To all whom it may concern:

Be it known that I, WARREN N. BOWERS, of Jefferson township, in the county of Allen and State of Indiana, have invented certain new and useful Improvements in Gates; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 is a side view of the gate; Fig. 2, a reverse view of the gate; Fig. 3, a view of the gate open; Fig. 4, detail views of the beam, and Fig. 5 an end view partly in section.

This invention relates to improvements in gates, more particularly in sliding gates. Its object is to produce a gate which can easily and quickly be opened for foot-passengers or wagons.

The invention consists in the construction hereinafter set forth and described.

In the annexed drawings, the letters A A' indicate the gate-posts, between which is the way in which the gate B moves. This gate has the usual vertical and horizontal rails, b b' b'', and brace b''. Two of the horizontal rails extend at b' beyond the vertical rail b, so as to form catches which engage slots a in post A. The other post, A', is recessed out at a', and has at its bottom a pintle, a''. On this pintle a'' is hung one end of a beam, C, and on the outside of this end is secured a roller, D, whose axle d is turned up and extends above the beam. To the other end of this beam C is secured a flange, E, having a recess, e, between, in which is pivoted a roller, F, the periphery of which comes above the beam. Projecting from the top of this flange E is a pin, e'. At its inner end this flange is curved, as shown at e''. The beam C, with its flange, is placed in the gate-frame on the inside of the brace b'', the roller F bearing against the under side of the second rail from the bottom, the roller D, which is larger, bearing on both this rail and the bottom rail, and the upturned end of the axle d and the pin e' resting

against said second rail and forming guide-pins to keep the parts in line. On the under side of the flange are cut notches h, in one of which is placed the loop h' of a chain or wire, H, which passes outside of the flange, and also through the recess k, between the flange and beam, and is secured by a loop, k', which passes over a button, K, at the top of post A'. On the top of the beam C is made a projection or catch, c, and a latch, L, hinged to the gate, is adapted to engage such projection or catch. This latch is operated by a cord, l, which passes through a loop, l', and a bar, l'', to the other side of the gate. The gate is thus supported upon the roller of the beam C, which is held by the pintle a'' and wire or chain H, the said chain also holding the gate in line as it comes on both sides of the latter. The gate being in the position shown in Fig. 1, it is only necessary to lift the latch L, disengaging it from the projection c, when the gate can be slid on the roller far enough to admit a foot-passenger, the brace coming up to the roller D. To admit vehicles the beam C is swung upon the pintle a'', the gate turning across the gateway, as shown in Fig. 2.

Having thus described my invention, what I claim is—

1. The sliding gate B, beam C, having the roller F, pin e', and roller D, with its upturned axle d, post A', and its pintle a'', the wire H, and button K, all connected and arranged substantially as described.

2. The combination of the sliding gate B, beam C, having the projection c, roller F, pin e', and roller D, with its upturned axle d, the post A', having the pintle a'', the wire H, button K, and latch L, with its cord l, all combined, constructed, and arranged as and for the purposes set forth.

In testimony that I claim the foregoing as my own I affix my signature in presence of two witnesses.

WARREN N. BOWERS.

Witnesses:

JOHN BAILYARD,

HIRAM HALLOPETER.
